UNITED STATES PATENT OFFICE.

JOHN M. CRUM, OF JOHNSTOWN, PENNSYLVANIA.

DOOR HANGER.

Application filed April 22, 1927. Serial No. 185,900.

This invention relates to improvements in door hangers, and more particularly to door hangers for garages and freight cars and the like.

5 An object of the invention is to provide an improved door hanger for garages and freight cars, in which the roller bearing is supported and protected in a suitable hood formed integrally with the body of the 60 hanger.

10 Another object of the invention is to provide a door hanger for garages and freight cars which is adapted to co-operate with an improved form of track and bumper mechanism for limiting the movement of the 65 hanger and door supported thereon.

15 A further object of the invention is to provide a door hanger for garages and freight cars, which will be so arranged to provide a 70 covering hood for the roller bearing, and a guide roller carried by the body portion of the hanger and adapted to engage the lower surface of a track to limit the upward movement of the hanger.

20 Other objects will appear as the description 75 proceeds.

In the accompanying drawings which form a part of my application,

25 Figure 1 is a front view of my preferred 80 form of door hanger showing the same in connection with a track and bumper for limiting the travel of the hanger;

30 Figure 2 is a sectional view taken on the 85 line 2—2 of Figure 1 looking away from the door bumper;

35 Figure 3 is an end view of the track and 90 bumper;

40 Figure 4 is a top view of a spacing block 95 used with the track for holding the same in the proper position with respect to the side of a freight car or the like;

45 Figure 5 is a front view of a door hanger 100 similar to that illustrated in Figure 1, but provided with two roller bearings and hoods therefor;

50 Figure 6 is a front view of a door hanger 105 showing a slightly modified form applied to the bottom of a door;

55 Figure 7 is a sectional view taken on the 110 line 7—7 of Figure 6;

Figure 8 is still another modified form of door hanger which will be attached to the face of a door and also to one of the batten strips thereof;

55 Figure 9 is a front view of a modification 115 of my door hanger showing the use of two

roller bearings with protecting hoods, the same being supported upon an angled bolt, the same being secured in a bracket at the top of a door, and

60

Figure 10 is a sectional view taken on the line 10—10 of Figure 9.

Like characters of reference are used throughout the following specification and the accompanying drawings to designate 65 corresponding parts.

My improved door hanger illustrated in Figs. 1 and 2 of the drawings comprises a body portion 1 which is provided at its upper end with a hood member 2. An axle member 3 is adapted to be mounted transversely of the hood 2 and is securely held in position by means of a pin 4. An oil passage 5 is provided adjacent the shaft 3 so that the same can be thoroughly lubricated. 75 The roller bearing 6 is provided with a centrally disposed annular flange and oppositely disposed bearing surfaces at either side of said flange, which are adapted to rest upon the track member 7. A bushing 8 is provided for the roller bearing 6 and is adapted to contact with the shaft 3. The roller bearing 6 may be formed integrally as illustrated 80 or may be formed of a plurality of roller members suitably secured together.

85

The track 7 comprises spaced angle members 9 which extend laterally at their upper surfaces and provide co-operating bearing surfaces for the roller bearing 6. These angle members 9 are spaced by means of the 90 collars 10 mounted upon the bolts 11. A plurality of spacing blocks 12 are attached to the inner angle member 9 and space the same from the side of the freight car or the garage on which the said track is mounted. 95 The door for the freight car or garage is designated 13, and is attached to the body portion of the hanger by means of the bolts 14.

A bumper 15 is removably positioned at the end of the track 7 and is provided with a cushioning surface 16 of rubber or other shock-absorbing material. The bumper 15 is formed with suitable re-inforcing webs so as to suitably strengthen the same to receive and withstand any ordinary shock.

100

A modified form of door hanger is illustrated in Fig. 5 of my drawings and comprises a body portion 17 and a plurality of integrally formed spaced hoods 18 in which the roller bearings 19 are mounted. It will 110 be understood that the roller bearings 19 are mounted in the same manner as the bearings

105

110

6 in the form of hanger illustrated in Figs. 1 and 2 of the drawings.

A web member 20 is formed integrally with the body portion 17 and extends laterally therefrom, and provides an abutment for the upper surface of a door to properly position the hanger on the door. Openings 21 are formed through the body portion 17 to receive suitable means for attaching the hanger to the door. Upwardly extending ears 22 are formed integrally with the web member 20 at its opposite ends and are provided with centrally disposed openings 23 through which bearing pins 50 are adapted to be positioned. These bearing pins are arranged to extend transversely of the track and below the same when the hanger is in operative position on the track, thereby limiting the upward movement of the said hanger.

In Figs. 6 and 7 I have illustrated a still further modification of a door hanger which is adapted to be attached to the lower surface of a door. The hanger comprises a body portion 24 and a depending hood member 25. A shaft 26 is disposed transversely of the hood member 25 and supports the roller bearing 27 so that the same may co-operate with and roll on the track 7. A suitable oil passage 28 is provided for lubricating the shaft 26 and bearing 27. It will be observed that the track 7 is secured to the garage or freight car 29 by means of the long bolts 30 which extend from the outside surface of the track, through the same and are firmly embedded in the said garage or freight car.

The door hanger illustrated in Fig. 8 of the drawings is adapted to be secured to the face of a door and is provided with a forwardly extending web 31 which will be secured to the end of a batten strip on the door. The body portion 32 of the hanger is provided with a forwardly extending hood 33 in which the roller bearing 34 is mounted. It will be understood that this form of door hanger may be used at either side of the door and at the top or bottom thereof.

The door hanger illustrated in Figs. 9 and 10 of the drawings is quite similar to that form of hanger illustrated in Fig. 5 of the

drawings, with the exception that instead of the downwardly extending body portion shown in Fig. 5 for attaching the hanger to the door, I now provide a bracket member 35 which will be secured to the door and an angled bolt 36 which will be carried by said bracket and attached at its free end to the hanger. The hanger is provided with a body portion 37, spaced hoods 38 and roller bearing 39 mounted transversely of said hoods. The body portion 37 is also provided with the laterally extending web 40 which carries the ears 41 at its opposite ends, which in turn are adapted to support the bearing rods disposed beneath the track for limiting the upward movement of the hanger. It will be seen that the door 42 is adjustable vertically with respect to the hanger 37.

Many minor changes in detail of construction may be resorted to without departure from the spirit of the invention.

Having thus described my invention what I claim as new and desire to secure by Letters Patent of the United States is:

1. A door hanger for freight car doors and the like, comprising a body portion, spaced hoods formed thereon, shafts mounted transversely of said hoods, roller bearings revolvably mounted on said shafts, a forwardly extending web integrally formed on said body portion and disposed below said roller bearings, means carried on said web for limiting the vertical movement of said hanger, and adjustable means for supporting said hanger from said web.

2. A door hanger for freight car doors and the like, comprising a body portion, spaced hoods formed thereon, shafts mounted transversely of said hoods, roller bearings revolvably mounted on said shafts, a forwardly extending web integrally formed on said body portion and disposed below said roller bearings, means carried on said web for limiting the vertical movement of said hanger, a bracket on said door, and an angled hook member adjustably positioned between said web and bracket.

In testimony whereof I affix my signature.

JOHN M. CRUM,
